(57) **CLAIM**

The ornamental design for a volatile dispenser element, as shown and described.

DESCRIPTION

In preferred embodiments the nature of this product is as a housing for an electric heat activated dispenser of volatile actives, or a refill cartridge for use therewith, or the combination of such a housing and such a refill

FIG. 1 is a right, bottom, frontal perspective view of a volatile dispenser element in the form of a housing for a volatile dispenser embodying our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right, bottom, frontal perspective view of a second embodiment of our new design which is a volatile dispenser element in the form of a refill cartridge;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a right, bottom, frontal perspective view of a third embodiment of our new design which is a volatile dispenser housing with a refill cartridge installed thereon;

FIG. 16 is a right side elevational view thereof;

FIG. 17 is a left side elevational view thereof;

FIG. 18 is a front elevational view thereof;

FIG. 19 is a rear elevational view thereof;

FIG. 20 is a top plan view thereof;

FIG. 21 is a bottom plan view thereof;

FIG. 22 is a right, bottom, frontal perspective view of a volatile dispenser element in the form of a second housing for a volatile dispenser embodying our new design;

FIG. 23 is a right side elevational view thereof;

FIG. 24 is a left side elevational view thereof;

FIG. 25 is a front elevational view thereof;

FIG. 26 is a rear elevational view thereof;

FIG. 27 is a top plan view thereof;

FIG. 28 is a bottom plan view thereof;

FIG. 29 is a right, bottom, frontal perspective view of a fifth embodiment of our new design which is the second volatile dispenser housing with the refill cartridge of FIG. 8 installed thereon;

FIG. 30 is a right side elevational view thereof;

FIG. 31 is a left side elevational view thereof;

FIG. 32 is a front elevational view thereof;

FIG. 33 is a rear elevational view thereof;

FIG. 34 is a top plan view thereof; and,

FIG. 35 is a bottom plan view thereof.

The broken line representations of plug environment in FIGS. 2, 3, 5-7, 16, 17, and 19-21 are for purposes of illustration only, and form no part of the claimed design.
